WILLIAM DRAKE AND DANIEL SZANTAY, OF CHICAGO, ILLINOIS, ASSIGNEES TO SINKO TOOL AND MANUFACTURING COMPANY, OF CHICAGO, ILLINOIS, A CORPORATION OF ILLINOIS.

AUTOMATIC CIGAR LIGHTER.

Application filed November 18, 1925. Serial No. 69,816.

This invention relates to automatic cigar lighters of the type extensively used in automobiles wherein a lighter tip equipped with a fine wire or filament adapted to be rendered incandescent by the passage of an electric current therethrough is mounted on one end of the cord carrying the circuit wires, and the cord is, in turn, wound on a spring-actuated reel or drum journaled in the casing attached to the dash or other wall portion of the car body, and wherein also the casing contains circuit-controlling contacts which are separated when the cord is wound up and are brought into contact to close the circuit when the cord is drawn out of the casing in order to use the lighter.

One object of our present invention is to provide an improved circuit-opening and closing mechanism that will be simple in construction, inexpensive to manufacture, wholly automatic in its action and reliable and efficient in operation. Another object is to provide an improved mounting of the spring drum and the winding drum or reel in the casing which will simplify and cheapen the construction of these parts and their mountings as hitherto known. Still other objects and attendant advantages of the invention will be apparent to persons skilled in the art as the same becomes better understood by reference to the following detailed description, taken in connection with the accompanying drawings wherein we have illustrated an approved embodiment of the invention, and in which—

Fig. 1 is an outer side elevation of the casing and its attached tip holder;

Fig. 2 is an enlarged section on the line 2—2 of Fig. 1;

Fig. 3 is a reduced section on the line 3—3 of Fig. 2; and

Fig. 4 is a fragmentary sectional view similar to Fig. 2, showing a modification of the automatic contact mechanism.

Referring to the drawings, 10 designates a generally cylindrical sheet-metal casing closed on one side by a removable cap 11; said casing, as shown in Fig. 3, being formed with a tangentially offset portion 10' formed with a round opening 12 in which is entered and secured one end of an externally threaded tube section 13 equipped with nuts 14 and 15 by which said tube section, forming the shank or handle of the casing, may be

secured in the dash or other fixed wall of the car body. Mounted and secured coaxially in one side of the casing 10 by means of an external nut 16 is a bearing member 17, in which is journaled a trunnion 18 that is locked against displacement inwardly of the drum by a screw 19 passed radially through the bearing 17 into a circumferential groove 20 in the trunnion. On the inner end of the trunnion 18 is a short neck 21, on which is mounted centrally a spring drum of casing 22 and also a hollow winding drum 23 for the cord of the lighter, the end of the neck 21 being swaged over the adjacent walls of the drums 22 and 23 to rigidly clamp them on the trunnion. The drums 22 and 23 are additionally locked together to prevent relative rotation by an outwardly pressed lug 24 on the wall of one drum engaged with a hole 25 in the adjacent wall of the other drum. 26 designates the lighter cord adapted to be wound and unwound off and from the drum 23 under the pull of a clock spring 27 in the drum 22 and an outward pull on the cord 26; the spring 27 being anchored at its outer end to the periphery of the drum 22 and at its inner end anchored to the fixed bearing member 17 by means of the screw 19. One circuit wire of the cord may be grounded to the flange of the drum 23, as shown at 28, while the other is electrically connected by a binding screw 29 to a spring contact member 30. This contact spring 30 is mounted on a fibre disc 31 that is fitted into the winding drum 23 against an internal shoulder 23' on the latter and is locked against rotation by means of tongues 32 cut and bent inwardly from the metal of the drum through notches 33 in the periphery of the disc 31 and lipped over the outer side of the latter. The disc 31 is formed with a central square hole 34, and with a radial notch 35 communicating with the hole 34 and providing clearance for the inner end of the contact spring 30.

The cap or cover-plate 11 is formed with a central hole 36, through which extends a threaded rod 37, the hole 36 being of greater diameter than the rod 37, and the latter being supported by a pair of insulating washers 38, 39 that are clamped on the cover-plate 11 between an abutment nut 40 on the rod 37 and a washer 41 and tightening nut 42. A circuit wire 43 from the positive pole of

the battery or other source of current is clamped between the nut 42 and a binding nut 44.

Mounted on the inner end of the threaded rod 37 is a square nut 45 of a size to slidably fit the square hole 34 in the disc 31. One side of this nut forms a contact member that directly co-operates with the contact spring 30 to make and break the circuit 10 through the lighter.

The screw thread on the rod 37 is so related to the winding up and unwinding movements of the drum 23 that, when the drum 23 is rotated by the drawing out of the lighter cord, the nut 45, which is at the same time rotated on the threaded rod 37 by disc 31, will travel inwardly of the winding drum, and close the circuit between the nut 45 and the spring 30, the free end of the latter wiping over one side of the nut and maintaining the circuit closed until the concluding portion of the opposite winding movement of the drum. When the cord is wound up on the drum by the rotative impulse of the winding spring, the nut 45 travels in the opposite direction, and slightly before the cigar lighter, indicated at L on the lighter cord, comes to rest within the tubular socket member 18, the nut passes off 20 and out of contact with the spring 30, and the circuit is broken at that point.

In the manufactured article, since the drum trunnion is at one side only of the drum, the pull of the cord unavoidably creates a slight sidewise tilting tendency of the drum which would amount to approximately $\frac{3}{2}$ of an inch at the opposite side of the drum from the trunnion if said opposite side were wholly unsupported. Further reduction of this tilting tendency would involve such a tight fit of the trunnion in its bearing that the winding spring, unless made undesirably heavy, would not wind up the cord. To oppose this tilting tendency and reduce it to a negligible amount, the nut 45 has a clearance of about .005 inch in the aperture 34 of the disc 31, so that when the cord is wound up and unwound the disc 31 and nut 45 together form a support for the 40 side of the drum which is opposite the trunnion, reducing the tilting or canting movement to a negligible amount.

In Fig. 4 we have illustrated a slight modification in the form of the contacts, which however, embodies the same operative principle as that previously described. In this form of the invention, the contact spring 30' extends further into the drum 23 and terminates in a flat section 46 to which is attached, as by a metal rivet 47 an insulating washer 48, normally held by the spring against the inner side of the winding drum. The threaded rod 37' is made somewhat shorter than the rod 37 previously described,

and is hollowed out to receive a plunger 49 and a coil compression spring 50 in rear of said plunger. The plunger 49 is formed with a reduced forwardly projecting neck or stem 51 which passes through a hole of the same diameter in the outer closed end of 70 the square nut 45'. The plunger neck or stem 51 is in line with the rivet 47, and said rivet and plunger stem constitute the immediate circuit make and break contacts. In the operation of this form of the invention, when the cord is drawn out the unwinding movement of the drum advances the nut 45' toward the spring contact 46, which permits the spring 50 to simultaneously advance the plunger until the end of the plunger neck or stem strikes the stud whereupon the circuit is closed, and further rotative movement of the nut 45' in the same direction is without effect. The circuit remains closed during the winding up movement of the 85 drum until the outer end wall of the nut strikes the annular shoulder on the plunger at the base of its neck, whereupon the plunger is retracted by the nut against the thrust of the spring 50 and the circuit is 90 thus broken.

In both forms of the invention the circuit is opened and closed between a fixed contact and a movable contact actuated by a sliding nut which in turn is rotated in both directions by the cord winding drum.

Automatic circuit opening and closing devices have heretofore been known and used in cigar lighters of this general type; but, so far as we are aware, such devices have been quite complicated in structure and costly to manufacture; and the comparatively simple automatic circuit opening and closing mechanisms herein shown and described are believed to be not only novel, to the extent indicated in the appended claim, but to represent a considerable simplification and cheapening of devices of this character.

We claim—

In a cigar lighter of the character described, the combination of a casing, a hollow bearing member fixedly mounted in one side of said casing, a lighter cord drum having a trunnion on one side thereof journaled in said bearing member, a fixed contact carried by said drum, a threaded rod non-rotatably mounted in the opposite side of said casing, a nut mounted on said rod and adapted by its movements lengthwise of the latter to make and break contact with said fixed contact member, and a disc of insulating material fixedly mounted in the other side of said drum embracing and rotating said nut under the turning movements of said drum, said disc and nut forming a support for one side of said drum.

WILLIAM DRAKE.
DANIEL SZANTAY.
